CASING FOR REFRIGERATION SYSTEM
CONDENSING UNITS OR THE LIKE

Walter W. Hoyle, Fayetteville, N.Y., assignor to
Carrier Corporation, Syracuse, N.Y.

Filed Aug. 2, 1971, Ser. No. 168,517

Term of patent 14 years

Int. Cl. D23—04

U.S. Cl. D23—139

FIG. 1

FIG. 2

FIG. 3

FIG. 4

FIG. 1 is a front elevational view of a casing for refrigeration condensing units showing my new design;

FIG. 2 is a perspective view thereof on an enlarged scale;

FIG. 3 is a side elevational view thereof; and

FIG. 4 is a rear elevational view thereof.

I claim:

The ornamental design for a casing for refrigeration system condensing units or the like, substantially as shown and described.
